Apparatus for forming a series of spaced parallel grooves in the surface of a newly laid pavement slab characterized by engaging the surface of the pavement slab with a molding cylinder having a plurality of circumferential ribs formed thereon and moving the molding cylinder across the surface of the pavement slab while simultaneously rotating the molding cylinder about its longitudinal axis at a rate slightly greater than a free roll. Means are disclosed for preventing damage to the parallel edges of the pavement slab during the grooving process, and means are disclosed for simultaneously spraying water on the surface of the pavement slab and the surface of the molding cylinder during the grooving process.

APPARATUS FOR GROOVING PAVEMENT

BACKGROUND OF THE INVENTION

1. Field of the Invention

The invention relates generally to method and apparatus for treating the surface of concrete, and more specifically, but not by way of limitation, to method and apparatus for automatically forming parallel grooves in the surface of a newly laid pavement slab.

2. Brief Description of the Prior Art

It has become desirable in the construction of pavement slabs for highways and airport runways to provide grooves in the surface of the slab to provide runoff channels for water to prevent the tires of automobiles or aircraft from riding on the surface of the water on the pavement slab thereby causing loss of control of the vehicle. This phenomenon is known as aquaplaning.

Known examples of the prior art teach various systems for providing grooves in the surface of pavement slabs. One method of forming such grooves is to use a rotary saw blade to cut grooves in the surface of a cured pavement slab. This method is extremely slow and expensive. Another known method of achieving this objective is to draw a sledge, having spaced parallel ribs formed on the bottom side thereof, across the surface of a newly laid pavement slab to form grooves therein. Apparatus for practicing this method has proved somewhat unsatisfactory due to damage done thereby to the surface of the pavement slab. The prior art also teaches the use of cylinders having circumferential ribs formed therein which are rolled freely across the surface of a newly laid pavement slab to form grooves therein. This method has also proved unsatisfactory since it tends to force a portion of the newly laid pavement along in front of the molding cylinder which also damages the surface of the newly laid pavement slab. Yet another known prior art system utilizes the counter rotation of the molding cylinder as the molding cylinder is traversed across the surface of the newly laid pavement slab. This latter method, as well as the previously mentioned methods, provides less than satisfactory surface finish to the newly laid pavement slab.

SUMMARY OF THE INVENTION

The present invention contemplates a method of forming a series of spaced parallel grooves in the surface of a newly laid pavement slab having substantial parallel edge portions comprising the steps of engaging the surface of the pavement slab with the molding cylinder having a plurality of spaced circumferential ribs formed on the cylindrical surface thereof, pressing the molding cylinder into the surface of the pavement slab to imbed a portion of the ribs in the pavement and to press a portion of the cylindrical surface of the molding cylinder against the surface of the pavement, moving the molding cylinder over the surface of the pavement slab in a direction substantially normal to the longitudinal axis thereof and rotating the molding cylinder about the longitudinal axis thereof in the direction of movement over the surface of the pavement at a rotational rate greater than the rotational rate of the molding cylinder if rolled freely over the surface of the pavement.

An object of the present invention is to provide an improved method of forming a series of spaced parallel grooves in the surface of a newly laid pavement slab

which will provide a substantially smooth surface with parallel grooves formed therein.

Another object of the present invention is to provide an improved method of forming a series of spaced parallel grooves in the surface of a newly laid pavement slab which will not damage the surface of the pavement slab.

Yet another object of the present invention is to provide an improved method and apparatus for forming a series of spaced parallel grooves in the surface of a newly laid pavement slab which will neither damage the surface of the pavement slab nor damage the parallel edges of the pavement slab.

Another object of the present invention is to provide an improved apparatus for forming a series of spaced parallel grooves in the surface of a newly laid pavement slab which is of simple construction, is reliable in operation, and is economical to maintain.

Other objects and advantages of the present invention will be evident from the following detailed description when read in conjunction with the accompanying drawings.

BRIEF DESCRIPTION OF THE DRAWINGS

25 FIG. 1 is a plan view of the apparatus of the present invention.

FIG. 2 is a side elevation view of the apparatus of the present invention taken along line 2-2 of FIG. 1.

30 FIG. 3 is a front elevation view of the apparatus of the present invention taken along line 3-3 of FIG. 2.

FIG. 4 is a cross-sectional view taken along line 4-4 of FIG. 1.

35 FIG. 5 is a partial plan view taken substantially along line 5-5 of FIG. 4 to more clearly illustrate the rail assembly of the present invention.

FIG. 6 is an enlarged partial cross-sectional view taken along line 6-6 of FIG. 4 to more clearly illustrate the carriage and grooving assemblies of the present invention.

FIG. 7 is an enlarged partial cross-sectional view taken along line 7-7 of FIG. 6 to more clearly illustrate the carriage and grooving assemblies of the present invention.

45 FIG. 8 is an enlarged partial cross-sectional view taken along line 8-8 of FIG. 5 to more clearly illustrate construction details of the rail assembly of the present invention.

FIG. 9 is an enlarged partial cross-sectional view illustrating a typical configuration of the surface of the 50 molding cylinder of the present invention.

DESCRIPTION OF THE PREFERRED EMBODIMENT

55 Referring to the drawings, and to FIGS. 1-4 in particular, the apparatus of the present invention is generally designated by the reference character 10. The apparatus 10 generally comprises a frame assembly 12, a rail assembly 14 suspended beneath the frame assembly 12, a carriage assembly 16 carried by the rail assembly 14 and adapted for vertical movement thereon, and a grooving assembly 18 suspended beneath the carriage assembly 16.

60 The frame assembly 12 is provided with a support assembly 20 at each of the four corners thereof to support the frame assembly 12 in a generally horizontal position on the ground. Each support assembly 20 includes a support wheel 22 journaled thereon. Each sup-

port assembly 20 further includes a pair of mutually telescoping elements 24 and 26 which provide means for adjusting the height of the frame assembly 12 relative to the ground.

A power unit 28 is mounted on the frame assembly 12 and is drivingly connected to each support wheel 22 to provide forward or rearward movement of the apparatus 10 over the ground. The power unit 28 may be of any suitable type but preferably includes a diesel type internal combustion engine as the prime mover. The power unit 28 preferably includes a conventional hydraulic pump driven by the prime mover which is in turn connected by means of hydraulic lines (not shown) to a hydraulic motor 30 carried by each support assembly 20 and drivingly connected to each support wheel 22. A control console 32 is mounted on the frame assembly 12 and provides means for manual operational control of the apparatus 10 by an apparatus operator.

At each support assembly 20, the telescoping element 26, upon which a support wheel 22 is journaled, is free to rotate within the respective telescoping element 24 about a substantially vertical axis. This arrangement permits each support wheel 22 to be revolved about this same vertical axis thereby providing means of steering control for the frame 12. Each telescoping element 26 is provided with an elongated arm 34 which is fixedly secured at one end thereof to the respective telescoping element 26. The opposite end of each elongated arm 34 is pivotally secured to a hydraulically actuated steering linkage 36 of conventional design which need not be described in detail herein. A first sensor assembly 38 and a second sensor assembly 40 are mounted on the frame assembly 12. The sensor assemblies 38 and 40 are adapted to engage a stringline 42 to provide automatic steering control of the apparatus 10. This method of position feedback control of the apparatus 10 is well known and is contained in U.S. Pat. No. 3,423,859, to G. W. Swisher Jr., et al. and will, therefore, not be described in detail herein.

The rail assembly 14 is suspended beneath the frame assembly 12 by means of a pair of telescoping struts 44. The upper portion 46 of each telescoping strut 44 is fixedly secured to the frame assembly 12, while the lower portion 48 of each telescoping strut 44 is pivotally secured to the rail assembly 14. Each telescoping strut 44 is equipped with a two-way hydraulic cylinder 45 disposed within interconnecting the upper portion 46 and the lower portion 48 thereof to alternately raise and lower the rail assembly 14 relative to the frame assembly 12.

As shown in FIG. 5, the rail assembly 14 comprises a pair of elongated parallel rails 50 and 52 rigidly secured together by a plurality of cross members 54. At one end 56 of the rail assembly 14 a cross member 58 rigidly interconnects the elongated rails 50 and 52, while at the opposite end 60 of the rail assembly 14 a cross member 62 rigidly interconnects the elongated rails 50 and 52. The elongated rails 50 and 52 are preferably formed of channel steel having a C-shaped cross section. It will be noted that the flanges of the elongated rails 50 and 52, respectively, extend horizontally away from one another.

The elongated rail 50 comprises four segments 64, 66, 68, and 70, while the elongated rail 52 comprises four rail segments 72, 74, 76, and 78. The ends of abutting rail segments are typically secured together by

means of a pivotal pin connection 80 beneath the lower flanges thereof. The upper flanges of abutting rail segments are adjustably secured together by means of a turnbuckle assembly 82 secured at the opposite ends thereof to respective brackets 84 formed on the upper flanges of the adjacent rail segments. This particular arrangement provides the capability of adjusting the alignment of the rail segments of the respective elongated rails 50 and 52. This arrangement also provides the capability of substituting rail segments of various lengths to provide virtually any desired length of the rail assembly 14. It should be noted that, while a simple mechanical turnbuckle assembly 82 is disclosed herein for the purpose of adjusting the alignment of the rail assembly 14, it may be desirable, in certain applications, to substitute a two-way hydraulic cylinder for one or more turnbuckle assemblies to provide automatic adjustment of the rail assembly 14.

The previously mentioned lower portion 48 of each telescoping strut 44 is pivotally secured to a respective cross member 86 rigidly interconnecting the elongated rails 50 and 52. See FIG. 8. A bracket 88 extends upwardly from each elongated rail 50 and 52 adjacent the point of intersection with the cross member 86. A tension coil spring 90 interconnects each bracket 88 and the respective lower portion 48 of a telescoping strut 44. The coil springs 90 are of substantially the same spring rate and provide means for biasing the rail assembly 14 into a plane substantially parallel to the substantially horizontal frame assembly 12.

A drive shaft 92 is journaled at the opposite ends thereof in one end 56 of the rail assembly 14. A pair of sheaves 94 are keyed to the drive shaft 92 and are adapted to frictionally engage a steel cable wrapped therearound. A drive motor 96, preferably a two-way hydraulic motor, is mounted on the end 56 of the rail assembly 14 and is suitably connected to the drive shaft 92, such as by a sprocket and chain drive, to provide rotational movement thereof. The drive motor 96 is suitably connected to the power unit 28, preferably by means of hydraulic lines, to receive power for rotating the drive shaft 92.

A pair of sheaves 98 are each journaled on a respective bracket 100 which is fixedly secured to the cross member 62 at the opposite end 60 of the rail assembly 14. The function of the drive motor 96, drive shaft 92, and sheaves 94 and 98 described above will be explained in greater detail hereinafter.

The carriage assembly 16 comprises a pair of parallel roller supporting members 102 and 104 which are rigidly secured to a pair of elongated parallel members 106 and 108 thereby forming a rigid rectangular frame. A pair of rollers 110 are horizontally journaled on the roller supporting member 102 and rollingly engage the inner surface of the lower flange of the elongated rail 50. A pair of rollers 112 are vertically journaled on the roller supporting member 102 and rollingly engage the web of the elongated rail 50. A pair of rollers 114 are horizontally journaled on the roller supporting member 104 and rollingly engage the inner surface of the lower flange of the elongated rail 52. A pair of rollers 116 are vertically journaled on the roller supporting member 104 and rollingly engage the web of the elongated rail 52. It will readily be apparent that the arrangement of the rollers 110, 112, 114, and 116 permits the carriage assembly 16 to rollingly traverse the entire length of the frame assembly 12 by rolling along the elongated rails

50 and 52. An end plate 118 rigidly interconnects the adjacent ends of the elongated parallel members 106 and 108. Another end plate 120, identical to end plate 118, rigidly interconnects the opposite adjacent ends of the elongated parallel members 106 and 108. A bracket 122 having outwardly and downwardly extending arms 124 and 126 formed on the opposite ends thereof is fixedly secured to the end plate 118. A second bracket 128 having outwardly and downwardly extending arms 130 and 132 formed on the opposite ends thereof is fixedly secured to the end plate 120. The function of the arms 124, 126, 130 and 132 will be explained in detail hereinafter.

A pair of substantially identical steel cables 134 and 136 are fixedly secured at the first ends 138 and 139 thereof to the elongated parallel member 106 of the carriage assembly 16. See FIG. 5. The cables 134 and 136 extend beneath the frame assembly 12 to the respective sheaves 98, upward and around the respective sheaves 98 across the upper portion of the rail assembly 14 to the respective sheaves 94 keyed on the drive shaft 92. The cables 134 and 136 extend around the respective sheaves 94 at least 1½ times and extend therefrom beneath the rail assembly 14 to the elongated parallel member 108 where the opposite ends 140 and 141 of the cables 134 and 136, respectively, are fixedly secured to the elongated parallel member 108 of the carriage assembly 16. The wrapping of the steel cables 134 and 136 around the respective sheaves 94 provides frictional engagement therebetween thereby causing the rotational movement of the sheaves 94 in response to the drive motor 96 to impart linear movement to the carriage assembly 16 along the rail assembly 14 via the cables 134 and 136. It will be readily apparent that rotation of the drive motor 96 in one direction will cause the carriage assembly 16 to roll along the rail assembly 14 in a corresponding linear direction while, alternately, rotation of the drive motor 96 in the opposite direction will cause the carriage assembly 16 to roll linearly along the rail assembly 14 in a corresponding opposite direction.

The grooving assembly 18 includes a support frame 142 and a molding cylinder 144 journaled thereon. See FIGS. 5 and 6. The support frame 142 includes an elongated horizontal member 146 with a downwardly extending vertical member 148 fixedly secured to one end thereof, and with a second vertical member 150 fixedly secured to the opposite end thereof and extending both upwardly and downwardly from the horizontal member 146. Angle brackets 152 and 154 are fixedly secured to the upper surface of the horizontal member 146 and extend upwardly therefrom in spaced parallel relation. Each bracket 152 and 154 includes a vertically aligned elongated slot 156 formed therein.

The support frame 142 is pivotally suspended beneath the carriage assembly 16 by means of bolts or pins 158 slidably extending through the slots 156 in the respective brackets 152 and 154 and fixedly secured in the respective end plates 118 and 120 of the carriage assembly 16. This means of attachment of the support frame 142 to the carriage assembly 16 permits the support frame 142 to pivot about a substantially horizontal axis relative to the carriage assembly 16, and to move substantially vertically relative to the carriage assembly 16 by means of a sliding action of the slots 156 relative to the bolts 158.

A coil tension spring 160 interconnects the outer end portion of each arm 124, 126, 130 and 132 of the carriage assembly 16 and the horizontal member 146 of the support frame 142. The springs 160 provide a constant spring bias to urge the support frame 142 into a substantially vertical pendant position beneath the pivotal connection between the support frame 142 and the carriage assembly 16.

A bracket 162 is fixedly secured to the upper end portion of the vertical member 150. A drive motor 164 is fixedly secured to the bracket 162 and a horizontally disposed drive shaft 166 extends outwardly therefrom through the brackets 162. A chain drive sprocket 168 is keyed to the drive shaft 166. The drive motor 164 is preferably a reversible hydraulic motor which receives its power through hydraulic lines (not shown) connected to the power unit 28. Although the drive motor is preferably of the hydraulic type, other suitable drive motors may be substituted therefor such as an electric motor.

The molding cylinder 144 includes a first shaft stub 170 secured to the first end portion 172 thereof and coaxial therewith. A second shaft stub 174 is secured to the second end portion 176 of the molding cylinder 144 coaxial therewith. The first shaft stub 170 extends through the vertical member 150 and is journaled therein in a suitable bearing 178. The second shaft stub 174 extends through the vertical member 148 and is journaled therein in a suitable bearing 180. A chain drive sprocket 182 is keyed to the outer end portion of the first shaft stub 170. A drive chain 184 drivingly engages the chain drive sprockets 168 and 182 thereby providing means for the rotation of the molding cylinder 144 in response to rotary power furnished by the drive motor 164.

A plurality of circumferential ribs 186 are formed on the cylindrical periphery 188 of the molding cylinder 144. The ribs 186 are preferably equally spaced along the periphery 188 of the molding cylinder 144 and are in parallel relation to one another.

In a preferred embodiment the molding cylinder 144 has a length of approximately 10 feet and a cylindrical diameter of approximately 10 inches. The circumferential ribs 186 are preferably spaced approximately 1½ inches apart along the cylindrical periphery 188 of the molding cylinder 144. The width of each circumferential rib 186 is preferably approximately ¼ inch and the height of each circumferential rib 186 from the periphery 188 of the molding cylinder 144 is also approximately ¼ inch. As shown in FIG. 9, the cross section of each circumferential rib 186 is substantially in the form of a triangle with a radius formed on the apex of the triangle and with fillets formed between the outer legs of the triangle and the periphery 188 of the molding cylinder 144.

It should be noted that the molding cylinder 144 may suitably be formed in any number of configurations, and the detailed description of a single preferred construction of the molding cylinder 144 should not be construed to limit the present invention in any way. It will be readily apparent to those skilled in the art that various forms of spacing and shaping of the circumferential ribs 186 on the molding cylinder 144 may be required to meet highway or runway design requirements set forth in various construction contracts.

It has been found that a suitable material for the construction of the molding cylinder 144 is aluminum pipe

having a nominal diameter of 10 inches. Other suitable materials may be used for the construction of the molding cylinder 144 including steel.

On each side of the frame 12 are mounted two vertically oriented struts 190 as shown in FIGS. 1, 2, 3 and 4. Each strut 190 is fixedly secured to the frame 12 by means of a pair of horizontal parallel members 192. Each strut 190 is in the form of a rectangular tube. A rectangular member 194 is received in each strut 190 and extends downwardly therefrom. The members 194 are adapted to move vertically within the respective strut 190 in telescopic fashion. Each member 194 is locked in a predetermined position within the respective strut 190 by means of a pair of hexagonal-headed cap screws 196, or the like, which are threadedly secured in the respective strut 190 and bear against the member 194.

The lower end portion 198 of each member 194 is sized and shaped to receive a horizontally disposed rectangular member 200 which is aligned substantially parallel to the previously discussed members 192. Each member 200 is locked in a predetermined position within the lower end portion 198 by means of a pair of locking cap screws 196, or the like, threadedly secured in the lower end portion 198 and bearing on the rectangular member 200.

The inwardly extending free ends 202 of the respective members 200 on each side of the frame assembly 12 are interconnected by a substantially flat plate 204. The plate 204 is preferably welded to the upper surface of the respective member 200 and extends inwardly from the free ends 202 thereof. The inner edge 206 of each plate 204 is aligned substantially with the longitudinal axis of the molding cylinder 144. Each plate 204 is preferably positioned on the respective members 200 such that it is inclined outwardly and slightly upwardly from a plane substantially parallel to the surface of the pavement slab from the inner edge 206 thereof as shown in FIG. 4. The length of each plate 204 along the edge 206 thereof is preferably at least one-half the length of the molding cylinder 144.

When properly positioned, the plates 204 extend inwardly over the respective adjacent outer edges of the concrete pavement slab to be grooved. The edge 206 of each plate 204 will be positioned slightly above the upper surface of the pavement slab.

Vertical adjustment of the rectangular members 194 within the respective struts 190 may be readily obtained by means of conventional screw jacks 208 installed in the respective upper end portions 210 of the struts 190. When proper vertical positioning is obtained by means of the screw jacks 208, the members 194 may be locked in proper position by tightening the respective cap screws 196 in the respective struts 190.

The previously described plates 204 and the structure for supporting the plates 204 beneath the frame assembly 12 provide simple and effective means for preventing the molding cylinder 144 from breaking out, or otherwise damaging the edge portions of the pavement slab during the grooving operation. It will be readily apparent that when the molding cylinder 144 nears an edge portion of the pavement slab it will engage a respective adjacent plate 204 and will be supported thereby above the edge portion of the pavement slab.

Under certain circumstances it may be desirable to spray the surface of the concrete pavement slab and/or

the peripheral surface 188 of the molding cylinder 144 with water. This may be accomplished by the addition of a water sprinkling apparatus comprising a pair of hollow sprinkler bars 212 which are rigidly secured to the outer end portions of the arms 124, 126, 130 and 132 of the carriage assembly 16 as shown in FIGS. 6 and 7. Each sprinkler bar 212 includes a plurality of sprinkler heads 214 mounted along the length of the sprinkler bar 212 in spaced relation. The sprinkler bars 212 are connected by means of water hoses (not shown) to a water supply tank 216 carried by the frame assembly 12. The length of each sprinkler bar 212 is preferably substantially equal to the length of the molding cylinder 144. In the preferred embodiment this length is approximately 10 feet. It should be noted that this sprinkler apparatus is also useful for washing the molding cylinder 144 after completion of a pavement grooving operation to remove concrete materials or the like which may remain on the periphery thereof.

OPERATION OF THE PREFERRED EMBODIMENT

In operation, the apparatus 10 of the present invention is positioned over a concrete pavement slab as shown in FIGS. 1, 2, 3 and 4. The longitudinal axis of the apparatus 10 is positioned in substantial alignment with the longitudinal axis of the pavement slab. The plates 204 are then positioned by means of the previously described adjustments such that the inner edges 206 thereof extend inwardly over the respective edge portions of the pavement slab and are positioned slightly above the upper surface of the pavement slab. The rail assembly 14 is then lowered beneath the frame assembly 12 by means of the telescoping struts 44 until the grooving assembly 18 rests on one of the plates 204. The drive motor 96 is then activated to move the carriage assembly 16 across the apparatus 10 on the rail assembly 14 in the direction of arrow 218 in FIG. 3, with the molding cylinder 144 pressing into the upper surface of the pavement slab as it moves off the supporting flat plate 204.

As the drive motor 96 is actuated, the drive motor 164 is also actuated to rotate the molding cylinder 144 in the direction of arrow 220 in FIG. 3, about its longitudinal axis in the support frame 142 of the grooving assembly 18. The rotational speed of the drive motor 164 and the direction of rotation of the drive motor 164 is adjusted such that the molding cylinder 144 is rotated in the direction of free roll across the surface of the pavement slab but at a rotational speed slightly greater than that of a free roll. The rotation of the molding cylinder at a speed slightly greater than that of a free roll has been found by experimentation to provide optimum grooving of the surface of a concrete pavement slab.

When the carriage assembly 16 has traversed the full width of the apparatus 10, the molding cylinder 144 engages the flat plate 204 on the side of the apparatus 10 opposite its starting point and the drive motors 96 and 164 are stopped. The apparatus 10 may then be moved forward a distance approximately equal to the length of the molding cylinder 144. The process, described above, may then be reversed with the molding cylinder 144 traversing the pavement slab in the opposite direction of arrow 222 in FIG. 4 but, as noted above, the molding cylinder 144 will be rotated in the direction of arrow 224 in FIG. 4 by the drive motor 164 at a rotational rate slightly greater than that of a free roll. This

process may be repeated any number of times to provide transverse grooving in the surface of a concrete pavement slab.

If conditions warrant, water may be introduced into the sprinkler bars 212 from the water supply tank 216 during the traversing of the molding cylinder 144 and a desired amount of water will be sprayed on the pavement slab and the molding cylinder 144 through the sprinkler heads 214.

It should be noted that the coil tension springs 160 will provide a constant downward pressure of the molding cylinder 144 on the surface of the concrete pavement slab during the grooving operation, while permitting the molding cylinder 144 to accommodate any slight irregularities in the surface of the concrete slab such as may be encountered in a crowned pavement slab.

Under certain circumstances it may also be desirable to traverse the same grooves in the pavement slab more than once with the molding cylinder 144. It will be readily apparent that this may be accomplished by simply reversing the drive motors 96 and 164 as noted above to reverse the direction of traverse over the same grooves.

If it is desired to make all traverses across the pavement slab in the same direction, this may be accomplished in the following manner. The rail assembly 14 is first raised, after the initial traverse, a sufficient amount for the molding cylinder 144 to clear the surface of the pavement slab. The drive motor 96 is then reversed to move the carriage and grooving assemblies 16 and 18 back to the starting point. The apparatus 10 is then moved forward, if desired, to the next grooving position on the pavement slab. The rail assembly 14 is then lowered to its proper grooving position and the grooving process is repeated as described above.

It will be readily apparent that the invention is well suited to meet the previously stated objectives contained herein. Changes may be made in the construction and arrangement of parts or elements of the apparatus as disclosed herein without departing from the spirit and scope of the present invention.

What is claimed is:

1. An apparatus for forming a series of spaced parallel grooves in the surface of a newly laid pavement slab 45 having substantially parallel opposite edge portions comprising:

a machine having opposite side portions, a front end portion and a rear end portion, and movable longitudinally over said pavement slab;

a molding cylinder having opposite end portions and disposed intermediate said machine and said pavement slab, said molding cylinder having a longitudinal rotational axis and having a plurality of spaced circumferential ribs formed on the cylindrical surface thereof;

means for journaling said molding cylinder to said machine with the longitudinal rotational axis thereof in substantial alignment with the direction of movement of said machine over said pavement slab;

means for raising said molding cylinder above said pavement slab;

means carried by said machine for pressing said

molding cylinder into the surface of said pavement slab;

means carried by said machine for moving said molding cylinder over the surface of said pavement slab; means carried by said machine for rotating said molding cylinder about the rotational axis thereof in the direction of movement over the surface of said pavement slab at a rotational rate greater than the rotational rate of said molding cylinder if rolled freely over the surface of said pavement slab; and, means carried on each side portion of said machine for preventing the circumferential ribs of said molding cylinder from intersecting the respective edge portions of said pavement slab, said means comprising a flat plate secured to each side portion of said machine, each plate having an inwardly extending edge portion positioned above and slightly inwardly of the respective adjacent edge portion of said pavement slab, and each plate lying in a plane substantially parallel to the surface of said pavement slab.

2. The apparatus as defined in claim 1 wherein said means for journaling said molding cylinder to said machine comprises:

a subframe having opposite end portions, said molding cylinder being journaled at the opposite end portions thereof in the respective opposite end portions of said subframe;

connecting means interconnecting said subframe and said machine for supporting said subframe beneath said machine in a manner permitting movement of said subframe alternately from a position adjacent to one side portion of said machine to a position adjacent to the opposite side portion of said machine; and

wherein said means carried by said machine for rotating said molding cylinder about the rotational axis thereof is characterized further to include: a drive motor mounted on said subframe and drivingly connected to said molding cylinder for rotation thereof.

3. The apparatus as defined in claim 2 wherein said drive motor is reversible for rotation of said molding cylinder in either direction relative to said subframe.

4. The apparatus as defined in claim 2 wherein said subframe is characterized further to include:

a carriage assembly connected to said connecting means;

a support frame, having opposite end portions, pivotally secured to said carriage assembly and depending therefrom, said molding cylinder being journaled at the opposite end portions thereof in the opposite end portions of said support frame;

spring means interconnecting said carriage assembly and said support frame for urging said support frame into a substantially pendant position beneath said carriage assembly about the axis of pivotal securing therebetween.

5. The apparatus as defined in claim 4 wherein the axis of pivotal securing between said carriage assembly and said support frame is substantially parallel to the longitudinal rotational axis of said molding cylinder.
